UNITED STATES PATENT OFFICE.

HARRY A. SIPRELLE, OF CLEVELAND, OHIO, ASSIGNOR OF THIRTY ONE-HUNDREDTHS TO GERTRUDE SIPRELLE AND TWENTY ONE-HUNDREDTHS TO A. M. McCULLOUGH, BOTH OF CLEVELAND, OHIO.

HORSESHOE.

1,334,410.

Specification of Letters Patent. Patented Mar. 23, 1920.

Application filed October 3, 1918. Serial No. 256,657.

To all whom it may concern:

Be it known that I, HARRY A. SIPRELLE, a citizen of the United States, residing at Cleveland, in the county of Cuyahoga and 5 State of Ohio, have invented a certain new and useful Improvement in Horseshoes, of which the following is a full, clear, and exact description, reference being had to the accompanying drawings.

10 This invention relates to horseshoes, and more particularly to shoes having detachable calks. It is the general purpose and object of my invention to provide a shoe with calks which may be readily applied to 15 and removed therefrom, thus facilitating the repairing and replacing of such calks as occasion may require. More limitedly, my invention has for its object to so construct a horseshoe and one or more removable calks 20 therefor as to enable the latter to be securely and conveniently anchored, and to protect from injury the portions of the shoe with which the calk or calks interlock. I secure the foregoing objects in and through the 25 construction and arrangement of parts illustrated in the drawing forming part hereof, wherein Figure 1 represents a perspective view of a horseshoe constructed in accordance with my invention; Fig. 2, a bottom 30 plan view of said shoe, one of the heel calks being removed; Fig. 3 a front end elevation of such shoe; Fig. 4 a sectional view corresponding to line 4—4 of Fig. 3; Fig. 5 a detail in plan of a modification; and Fig. 6 35 a sectional detail corresponding to the line 6—6 of Fig. 5.

Describing by reference characters the various parts illustrated herein, 1 denotes the body of the shoe, which may be of any approved shape and dimensions. In view of the fact that the body of the shoe will not be subjected to such usage as will require frequent renewal, the same may be made 40 from a drop-forging. The shoe is shown as provided with the usual toe clip 2 and with three guideways, one at the toe portion and one at each of the heel portions of the shoe. The guideway 3 extends transversely of the bottom of the toe portion of the shoe 45 and is preferably countersunk, whereby a stop shoulder 4 is provided at one end thereof, constituting an abutment for the corresponding end of the toe calk. The guideway 3 is formed as a plane surface 50 against which the base of the calk is seated,

and along which it may slide as it is applied to and removed from the shoe. From the central portion of this guideway there projects a dovetail rib 5 extending transversely of the toe portion of the shoe, said dovetail 55 rib coöperating with a dovetail slot 6 in the base of the toe calk, which is shown as wedge-shaped or triangular in cross-section, the base thereof being a plane, whereby it may form a bearing with the guideway or 60 seat 3. In practice the dovetail slot 6 is slightly deeper than the rib 5, whereby the pounding of the calk will not be transmitted to the rib 5 but to the extended base provided by the guideway 3. The calk 7 will 65 be retained against movement in one direction in its guideway by the shoulder 4 and against movement in the opposite direction by means of a screw 8, preferably headless and threaded into the calk and projecting 70 into a recess 9' in the body of the shoe, a convenient location for such recess being at the junction of the dovetail rib 5 with the guideway 3. The parts will be so proportioned that the screw 8 will be generally 75 countersunk slightly below the outer surface of the calk.

Each heel portion of the shoe is shown as provided with a guideway 9 extending forwardly from the rear end thereof, said 80 guideways being similar to the guideway 3 and having each a central dovetail rib 10 projecting therefrom. The guideways 9 are preferably countersunk, there being a shoulder 11 at the forward end of each 85 guideway against which the forward end of a calk 12 may abut. Each calk 12 is provided with a dovetail recess 13 of some- 90 what greater depth than the coöperating rib 10, for the purpose described in connection with the calk 7. The shoulders 11 prevent forward movement of the calks 12 with reference to the body of the shoe, movement in the opposite direction being 95 prevented by means of a screw 14 in each 100 heel calk, which screw may be constructed and mounted in the same manner as the screw 8. The calks 12 are shown as wedge-shaped or triangular in section, it being understood that, for the purposes of my 105 invention, it is immaterial just what shape may be given to the outer external portions of the calks.

In Figs. 5 and 6 I have shown a heel calk which extends transversely of the shoe, one 110

end of the shoe only being shown. In this view, the guideway 9^a extends transversely of the heel end of the shoe, from the outer side of such shoe inwardly as far as a shoulder 11^a.
5 The dovetail rib 10^a extends transversely of the central portion of said guideway. The calk 12^a is constructed in the same manner as the calks 12 and is anchored by means of a screw 14^a similar in construction 10 and mode of application to the screw 14.

By the construction illustrated and described, it will be evident that each of the calks has an extended and firm bearing upon the supporting base provided by its 15 guideway; that it is anchored firmly in place; and that, in use, the dovetail ribs are protected against injury and defacement by the manner of mounting the calks thereon. This enables me, as occasion may require, 20 conveniently to remove any or all of the calks for the purpose of sharpening, repair, or renewal.

The calks may also be made of drop-forgings and the dovetail recesses thereof 25 as well as the dovetail ribs may be milled to secure proper sliding engagement therebetween. The bases of the calks and the guideways thereafter may be machined to

insure proper seating of the calks upon said guideways.

Having thus described my invention, what I claim is:—

1. A horseshoe having depressed plane guideways each provided with a central dovetail rib and having at one end thereof 35 a stop shoulder, formed by said depressions, a calk having a base coöperating with each guideway and provided with a dovetail recess of greater depth than the coöperating rib and abutting said shoulder, and a screw 40 threaded into each of said calks and adapted to engage the body of the shoe.

2. A horseshoe having depressed plane guideways each provided with a stop formed by said depressions and a central dovetail 45 rib, a calk for each of said guideways having a plane base and a dovetail recess extending into the body thereof from the central portion of such base and of greater depth than its coöperating rib and abutting 50 said stop, and means for securing said calks to said shoe.

In testimony whereof, I hereunto affix my signature.

HARRY A. SIPRELLE.
